C. Eugene Barber
Inventor

United States Patent Office.

C. EUGENE BARBER, OF AUBURN, NEW YORK, ASSIGNOR TO SHELDON AND COMPANY, OF SAME PLACE.

Design No. 3,612, dated August 17, 1869.

DESIGN FOR A TRADE-MARK.

The Schedule referred to in these Letters Patent and making part of the same.

To all whom it may concern:

Be it known that I, C. EUGENE BARBER, of Auburn, in the county of Cayuga, and State of New York, have invented a new and original Design for a Trade-Mark; and I do hereby declare that the following, taken in connection with the drawings which accompany and form part of this specification, is a full, clear, and exact description of my said invention.

My design consists of a double anchor, united by a single shank, as shown, and having a single ring at the centre of such shank.

A represents the shank;

B, the ring;

C C, the curved arms; and

D D D D, the barbs or flukes upon the ends of such arms, each pair of flukes pointing or curving toward the other.

I propose to use this trade-mark both as a printed or engraved design upon cards, letter or bill-heads, or in any similar manner, or as a brand, to be placed upon manufactured articles, or in any other way where it may be found desirable as a designating trade-mark.

I more particularly apply this trade-mark to iron and steel axles, and to the business connected therewith.

What I claim as my invention, and desire to secure by Letters Patent, is—

The design for a trade-mark herein set forth.

C. EUGENE BARBER.

Witnesses:

C. L. SHELDON,
SAM'L. F. REYNOLDS.
